UNITED STATES PATENT OFFICE.

CLARENCE E. RISHEL, OF CHAMA, TERRITORY OF NEW MEXICO.

REVERSIBLE ECCENTRIC.

No. 829,933.

Specification of Letters Patent.

Patented Aug. 28, 1906.

Application filed October 2, 1905. Serial No. 281,024.

To all whom it may concern:

Be it known that I, CLARENCE E. RISHEL, a citizen of the United States, residing at Chama, in the county of Rio Arriba and Territory of New Mexico, have invented certain new and useful Improvements in Reversible Eccentrics, of which the following is a specification.

This invention relates to certain improvements in that type of valve-reversing mechanism for engines wherein the reversal of the direction of motion is effected by the shifting of an eccentric connected with the valve; and it consists in certain peculiarities in the construction and arrangement of parts and in certain novel combinations of elements substantially as hereinafter described, and particularly pointed out in the subjoined claims.

The main or ultimate object of the invention is to provide a reversing mechanism of the type stated which will be of the highest efficiency.

Among the subsidiary objects of the invention the following may be mentioned: First, to provide a reversing-valve gear comprising a shifting eccentric adapted to be moved across the shaft, which eccentric in its movement from either side of said shaft to the other side thereof will preserve its lead of the valve; second, to provide means between the shaft and the eccentric and between said shaft and the eccentric-adjusting wedges for properly guiding said eccentric and wedges in the predetermined movements, thereby adding to the efficiency and durability of the gear; third, to provide a reversing-valve-gear mechanism adapted to be used on locomotive-axles and which will be unaffected by movement laterally of said axle in so far as transmitting any movement therefrom to the valve-rod is concerned. These objects are well accomplished by the construction illustrated in the accompanying drawings, which construction has been selected to exemplify what is at present regarded as the best embodiment of the invention.

In said drawings, Figure 1 is a plan view showing the invention applied to a locomotive. Figs. 2 and 3 are detail views of an axle or shaft with the shifting eccentric and its operating means therein, respectively, showing the same at the extremes of their positions, said means being viewed from the side opposite that upon which is located the means for sliding the wedges. Fig. 4 is a

horizontal section through the eccentric and its operating mechanism.

The same reference characters designate the same parts in the several views.

A designates the driving-shaft of the engine, which is journaled in bearings secured to a part of the engine-frame B. Mounted upon said shaft A is the eccentric C, provided with an eccentric-strap D, the rod d of which is connected with the valve-rod (not shown) preferably by the means hereinafter specified.

It will be understood that the eccentric is adjustable on the shaft and that its adjustment causes a corresponding movement of the valve, which effects a reversal of the engine. This adjustment of the eccentric is transversely of the shaft A and is effected by means which include wedges E E' and devices for sliding said wedges longitudinally of the shaft, which devices may be desirably composed of a sliding collar F, having a groove f, and bent lever G, fulcrumed between its ends (at g) on a fulcrum-bar b and having at one end a yoke g' and at its other end a reach-rod H, by which it is connected to the reversing-lever. (Not shown.)

It is apparent that the wedges E and E' are suitably secured to opposite sides of the collar F, for example, by providing them with arms e e', screwed to said collar, as shown. It is further apparent that the yoke g' partially embraces said collar and engages the grooved portion f thereof. The inclined or wedge-shaped edges of the wedges E E' extend reversely with each other, one, as E, having its end of greatest diameter presented toward the collar F, while the other, as E', has its end of least diameter located toward said collar. Said inclined edges of the respective wedges bear upon opposite inner walls of the central aperture c of the eccentric C, the surface of each of which walls preferably extends in diverging planes outwardly from a place near the center thereof, as shown at 1 and 2 in Fig. 4, in order to assure proper operation of the parts.

The edges of the wedges opposite their inclined ones are flat and bear upon contiguous edges of a bearing-block I, which is fixedly mounted on the shaft A and has grooves or passages i in its said edges, which grooves or passages receive the portions of the wedges which are contiguous to and on opposite sides of said shaft A and guide said wedges in their movements.

The other edges or sides i' of the bearing-block I bear upon the contiguous walls 3 and 4, respectively, of the aperture c in the eccentric C. Attention is called to the fact that said walls 3 and 4 form segments of circles which are concentric with each other and eccentric to the axis of the shaft A, on opposite sides of which they are arranged, and the edges i' of the bearing-block I are of shape corresponding to said walls 3 and 4, one of said edges i' being convex and the other concave and the curvatures of both being alike, whereby they bear throughout their lengths upon the concave wall 3 and convex wall 4, respectively, of said aperture c . The sides i' of the bearing-block I are preferably prolonged above and below said convex and concave edges, respectively, and engage the sides of the eccentric C, thus forming channels or grooves in opposite sides of said block, which receive portions of said eccentric contiguous to the aperture c therein, and of which channels or grooves the edges 3 and 4 form the beds or bases. It will now be seen that when it is desired to reverse the engine from or into the proper direction of movement of its parts the engineer shifts his reversing-lever in the proper direction, thus sliding the collar F toward or from the eccentric, as the case may be, and correspondingly adjusting the wedges E and E', which move the eccentric bodily across the shaft A and cause it to operate the valve in the well-known manner to effect the reversal desired. Attention is called to the fact that the bearing-block I causes the eccentric in passing from either of its positions across the center to travel in a curvilinear direction, which causes it to turn slightly ahead, and thereby increases the lead of the valve and at the same time decreases the travel of the same. The eccentric crosses the shaft at right angles with the crank-pin. In other words, the eccentric travels ninety degrees ahead of the crank-pin. As this would only overcome the lap of the valve and does not give any lead or opening and to turn the eccentric farther ahead on the shaft, as in the case of a single eccentric, would throw the travel that much behind when reversed, I accomplish the required lead by making the hole in the bearing-block back of its center as it stands in starting position with crank-pin in center throwing the whole eccentric ahead, and as the same side is always the driving side of my eccentric the lead will be the same when reversed. If it were not for the curved motion and the eccentric moved straight across the shaft, it would hold its lead on the forward stroke and lose it on the backward stroke as it was drawn toward the center.

For purposes of exemplifying the invention it is illustrated as applied for use on a

locomotive in which the axles shift endwise. In such instance the shaft A is the locomotive-axle and the fulcrum-bar b is separate from the engine-frame and is employed to overcome the tendency of continual shifting of the wedges and consequent shifting of the valves by the shifting of the axle. Said fulcrum-bar is mounted on the axle at b' by suitable means, which cause it to partake of the lateral but not of the rotative movements of said axle, and its connection with the lever G is such that it communicates said lateral movement to the latter. Said bar may have bearings in a supporting-bracket fixed either to the frame or to the boiler, and in which bearings it is adapted to slide.

A suitable means for connecting the eccentric-rod d with the valve comprises a rock-shaft J, to which is fixed a rocker-arm K, which is connected with said eccentric-rod, as shown at k, and in practice is also suitably connected with the rod of the valve. (Not shown.)

Having thus described the invention, what I believe to be new and desire to secure by Letters Patent, and what I therefore claim, is—

1. A reversing-valve gear for engines, comprising a shifting eccentric having an aperture opposite sides of which are formed with curvilinear walls, a shaft extending through said aperture, a bearing-block mounted on said shaft and having opposite edges curved to correspond with said curvilinear walls and engaging the same, sliding wedges arranged on opposite sides of the shaft and having their inclined edges engaged with the other walls of said eccentric and their other edges engaged with said block, and means for sliding said wedges.

2. A reversing-valve gear for engines, comprising a shifting eccentric having an aperture two opposite sides of which are formed with curvilinear walls, a shaft extending through said aperture, sliding wedges arranged on opposite sides of said shaft and having their inclined edges engaged with the other walls of said aperture, means for sliding said wedges, and a bearing-block mounted on said shaft within said aperture and provided on all of its edges with grooves, two of which receive the contiguous portions of said wedges and the other two of which receive the portions of said eccentric contiguous to the curvilinear walls of said aperture and are curved to correspond with and engage the latter, and means for connecting said eccentric with the rod of the valve to be shifted thereby.

3. The combination with a locomotive-axle, of a reversing-valve-gear mechanism mounted thereon and partaking of the lateral movements thereof, means for imparting movement to said valve-gear mechanism with relation to said axle for the purpose

specified, said means also partaking of the lateral movement of said axle.

4. In a device of the character described, the combination with an engine-shaft, of 5 wedges slideable longitudinally with relation to said shaft, an eccentric having an opening formed therethrough with which said wedges engage to shift said eccentric transversely of the shaft and means for turning said eccen-

tric bodily upon said shaft during such shifting motion. 10

In testimony whereof I affix my signature in presence of two witnesses.
